(57) **CLAIM**

The ornamental design for a body of a television camera, as shown and described.

DESCRIPTION

FIG. 1 is a front, top and right side perspective view of a body of a television camera, showing my new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is a rear elevational view thereof, with a cover of an auxiliary operating section being opened; and,
FIG. 9 is a right side elevational view thereof, with the cover of the auxiliary operating section in the open state.
